UNITED STATES PATENT OFFICE.

ALPHA LANGSTON, OF STRAUGHAS, INDIANA.

SEWER-FORM.

1,127,030.

Specification of Letters Patent.

Patented Feb. 2, 1915.

Application filed March 30, 1914. Serial No. 828,272.

To all whom it may concern:

Be it known that I, ALPHA LANGSTON, a citizen of the United States, residing at Straughas, in the county of Henry and State of Indiana, have invented certain new and useful Improvements in Sewer-Forms, of which the following is a specification.

This invention relates to forms for shaping the hollow interiors of concrete culverts and sewers, and the object of the invention is to provide a simple and inexpensive device which can be used in connection with a trench of the required over-all dimensions for otherwise shaping the product.

A further object of the invention is to provide a form which will be rigid and solid for any given adjustment, but which can be readily reduced in cross sectional area to loosen it from the concrete and enable it to be readily withdrawn after the concrete has become sufficiently set and firm to stand without the support of the form.

A further object of the invention is to provide a form which can be adjusted to different cross sectional areas to suit the desired size of the drain openings.

Another object of the invention is to provide a form which can be varied from circular to elliptical shape in cross section with either axis more or less shortened to suit the space available for the product, as, where a culvert must be so close to the surface of a roadway that a cylindrical opening of the requisite capacity would not leave roof-strength sufficient to support its load.

I accomplish the above, and other minor objects which will hereinafter appear, by the mechanism illustrated in the accompanying drawings, in which—

Figure 1 is a view in side elevation and partial longitudinal section of my invention in operative position for the construction of a culvert, and surrounded with concrete. Fig. 2 is an end view from the line 2—2 of Fig. 1. Fig. 3 is a vertical transverse section on the line 3—3 of Fig. 1. Fig. 4 is a view looking at the same end as in Fig. 2, but with the form reduced in diameter preparatory to its withdrawal from a finished culvert. Fig. 5 is an end view of a culvert with an elliptical opening, and with my invention in corresponding position to make an opening of that character. Fig. 6 shows a modified form of diametrical brace-rod, and Fig. 7 is a fragment of the wall of the

form showing the shape of the top opening for the passage of the brace-rod through it.

Like characters of reference indicate like parts throughout the several views of the drawing.

My device for forming the sewer or culvert opening comprises essentially a sheet metal cylinder with an open seam extending longitudinally thereof, with one edge of said seam lapped outside of the other, and means to uniformly lessen the diameter by increasing the lap of said edges when it is desired to remove the form from the recently molded product, and the invention also comprises means for retaining a given adjustment in diameter of the form and for bracing the form to prevent buckling or distortion.

The above-mentioned metal cylinder 8 will preferably be formed out of galvanized sheet iron or better still sheet steel having sufficient elasticity to return the cylindrical mold to a maximum normal expansion upon release after the cylinder has been reduced in diameter by drawing its lapped edges together. The length and diameter of the cylinder will vary with the corresponding dimensions of the product to be made, and while I prefer, if possible, to have the cylindrical form long enough to mold a culvert at one operation it is practicable to use a shorter form and make the finished product in two or more operations by removing the form from the finished part and re-using it successively.

The inner longitudinal edge 9 is provided with a series of hooks 10 for the attachment thereto of cables 11, each of which, after passing under sheaves 12, here shown as two in number are wound upon a rod 13. The rod 13 extends the entire length of the cylindrical form and is supported from the inner wall thereof by suitable journals 14 and serves as a windlass common to all of said cables, whereby they will all be simultaneously wound thereon. The purpose of the sheaves 12 is to change the direction of pull delivered through the cables to the edge 9 by the winding of the cables upon the rod 13, in order that the edge 9 may follow the opposite wall of the cylindrical form as closely as possible. Instead of a cable 11, as shown, a chain or rope or any other suitable flexible draw-line may be used.

A given adjustment of the rod 13 in order

to hold the windings of the cables thereon may be secured in various ways, and is obviously desirable. The means which I have shown in the drawings for accomplishing this purpose is a lug 15 on the rod 13 which is made to engage a recess or socket in one of the journal-boxes 14, by a longitudinal movement of the rod 13. The rod 13 is so mounted in the journals 14 as to permit 5 of the requisite longitudinal movement for this purpose, and also to permit of rotation for winding and unwinding the cables 11 thereon. The rod 13 is continued outside of one end of the cylindrical form and is 10 provided with a handle 16 on said projecting end for convenience in rotating the rod 13 and for adjusting it longitudinally to lock and unlock it. Secured to the outer side of the opposite longitudinal edge 17 of 15 my cylindrical form is a bar 18, through which, and also through the adjacent lapped edges 9 and 17 are holes for the passage of brace-bolts. The holes in brace-bar 18 and edge 17 are screw-threaded to receive the 20 correspondingly threaded end of the brace-bolt, but the holes through the edge 9 are not screw-threaded but are large enough to allow the brace-bolt to pass through freely. A series of said bolt holes 19 are formed at 25 each location at different distances from the edge 9 for the passage of the brace-bolts at correspondingly different laps of said edge as the diameter of the cylindrical form is thereby varied to make different size 30 openings in the culverts.

The brace-rods extend diametrically through the cylindrical form, and to that end the upper walls of the form are perforated, as shown at 20, Figs. 1 and 3, for the 40 passage of the brace-rods through said upper walls. The holes 20 are spaced apart circumferentially of the form to be in the right place diametrically opposite the corresponding hole 19 below, for the different 45 adjustments in diameter of the cylindrical molds.

The brace-rods which I prefer to use near the ends of the form where the nuts on them can be conveniently manipulated are as 50 illustrated in Figs. 1, 2 and 5 and comprise a bolt the body portion 21 of which is screw-threaded, and terminates at its lower end with a reduced screw-threaded portion 22 adapted to screw into the threaded hole in edge 9 and bar 18. This reduced portion 55 is provided with a lock-nut 23 which is screwed down against the end 17. The body portion 21 is provided with a pair of nuts 24 and 25, located on opposite sides of the upper wall of the form, and the brace-rod terminates with a hand-ring 26 at its 60 upper end for convenience in rotating the rod in screwing it in place.

End brace-rods as above described can be 65 used because the nuts 23, 24 and 25 are

easily reached from the end of the form, and the same kind of brace-rods can be used to advantage where the diameter of the form is such as to permit the entrance of a workman therein to set the inside nuts. But where the diameter is too small for a workman to enter I pass the brace-rod 27 70 (see Figs. 1 and 3), through a tube adjustable in its length which has been previously inserted within the form and which extends from top to bottom of the latter. This adjustable tube 28 is so formed by being in two telescoping members, the smaller and lower portion of which screws into the upper portion of larger diameter. The end of the lower portion rests against the bottom of the cylindrical form and the upper end of the upper and larger member is provided with outwardly extending diametrically opposite lugs 29 which contact the inner wall of the form at the top of the latter. The top opening 20 is large enough to allow the upper and larger member of the adjustable tube 28 to pass through, and extensions are provided for the passage of the lugs 29 to 80 the interior of the form, after which by a quarter turn of the upper tube the lugs are moved out of register with said extensions by which they were admitted and said lugs then act as supports for the top of the form, and the top and bottom of the form will be spaced apart the distance between the lower end of the lower tube and said lugs 29. The brace-rod 27 is screw-threaded substantially its entire length. It is passed through 85 a washer 30 on the outside of the cylindrical form, and above that is a nut 31 which is tightened down against the washer to force the top of the form firmly against the lugs 29. The brace-rod 27 terminates with a 90 hand-ring 26, at its upper end, for rotating it. A sleeve 32 is placed temporarily around the projecting upper ends of the brace-rods to hold the concrete material temporarily 95 away from them during the main operation 100 of molding the culvert, but after the body of the culvert has been molded and the concrete has become set the brace-rods are removed and after them the sleeves 32 are 105 removed, and before the form is withdrawn the recesses which remain in the 110 product where the sleeves 32 were are filled 115 with concrete.

Fig. 6 shows a modified form of brace-rod having its lower end reduced to provide 115 a shoulder which contacts the bottom of the form and presses the two lapped edges together by the draw of the thread on the reduced end of the rod entering the threaded hole in the bar 18. Instead of the telescoping tube as above described, through 120 which the brace-rod passes, the rod is provided with a transverse pin 34, the ends of 125 which project diametrically of the rod as a substitute for the lugs 29 on said tele- 130

scoping tube and these pin ends 34 support the top of the form and are introduced into the form through extensions of the hole for the passage of the bolt, in the same manner as has been described for the introduction of the lugs 29. A nut 35 on the upper screw-threaded portion of the brace-rod is moved down against the top of the form. The bar 18 may be a continuous one as shown in Fig. 1 or it may be in a plurality of shorter lengths as shown in Fig. 6 tapered at their ends for convenience in withdrawing the form from the finished product.

The operation of my invention is as follows: In making a culvert, for example, a trench is dug across the roadway of just the required over-all dimensions, and this forms the mold which gives the outside shape to the concrete. A bottom slab 36 of concrete is first formed, and as soon as it is sufficiently dry and set to stand the weight, my cylindrical form, previously adjusted to the desired size and shape, is lowered into the trench upon said slab 36. Concrete is then filled in around the form 8 in the manner shown in the drawing, the sleeves 32 being placed as the work progresses. After the concrete has become sufficiently firm the brace-rods and the sleeves 32 are removed, and then the walls 8 of the form are contracted by winding the cables 11 upon the rod 8 until the walls of the metal form are reduced in diameter and are sufficiently separated from the concrete to permit the form to be removed by being drawn out endwise. This is accomplished by hitching a team of horses to an end of the form by means of eyes 37 provided for that purpose on the inside of the form. In practice, the form is drawn out of the finished culvert without much difficulty. The bars 18 and 18' by being on the outer and under side of the form are held in their cement channels by the weight of the form 45 which prevents the rotation of the walls 8 when they are contracted by winding up the cables 11.

Where the culvert is so close to the top of the road-bed that there is not room enough to make one with a cylindrical interior of sufficient capacity, I am able, by the aid of the brace-rods and the nuts thereon to flatten the tubular form into an ellipse in cross section, of the desired radial dimensions, in 55 the manner shown in Fig. 5.

While I have described my invention with more or less minuteness as regards details of construction and arrangement and as being embodied in certain precise forms, I do 60 not desire to be limited thereto unduly or any more than is pointed out in the claims. On the contrary, I contemplate all proper changes in form, construction, and arrangement, the omission of immaterial elements 65 and the substitution of equivalents, as cir-

cumstances may suggest or necessity render expedient.

I claim:

1. In a form for concrete conductors, a one-piece sheet metal body portion having disconnected ends whereby the resiliency of the metal will spring or expand the sides, said body having its ends lapped at the bottom of the form, means for varying the lap of said ends, means for holding the position of the outer end during said variation and interior means for bracing the body.

2. In a form for making concrete conductors, a one-piece sheet metal body portion having disconnected ends whereby the resiliency of the metal will spring or expand the sides, said body being under strain and having its ends lapped at the bottom of the form, means for varying the lap of said ends, means for holding the position of the outer end during said variation and means for diametrically bracing the body.

3. In a form for making concrete conductors, a one-piece sheet metal body portion having disconnected ends, said ends being lapped at the bottom of the form, means operating on the inner end for varying the lap of said ends, means for holding the outer end during said operation and braces passing diametrically through the body into 95 said holding means.

4. In a form for making concrete conductors, a one-piece sheet metal body portion having disconnected ends, said ends being lapped at the bottom of the form, a windlass extending longitudinally through the inside of the body, flexible ties wound upon the windlass and connected with the inner one of said lapped ends, and means secured externally to the outer end for holding it 100 immovable while the inner end is moved by winding the flexible ties on the windlass.

5. In a form for making concrete conductors, a one-piece sheet metal body portion having disconnected ends, said ends being lapped at the bottom of the form, a windlass extending longitudinally through the inside of the body, flexible ties wound upon the windlass and connected with the inner one of said lapped ends, and means comprising sheaves between the windlass and 110 said inner end of the form to so change the direction of said flexible ties and secure a closer relation of the lapped members.

6. In a form for making concrete conductors, a one-piece sheet metal body portion having disconnected ends, whereby the resiliency of the metal will spring or expand the sides, said body being under strain and having its ends lapped, a windlass extending 115 longitudinally of and inside of the body, flexible ties wound upon the windlass and connected on the inner one of said ends, sheaves between the windlass and the inner end of the form to change the direction of 120 125 130

said flexible ties, a windlass lock, and means by a longitudinal movement of the windlass for locking a given position of the windlass.

7. In a form for making concrete conductors, a one-piece sheet metal body portion having disconnected ends, said ends being lapped, outside reinforcements on the outer lapped end, said outer end and reinforcements having threaded bolt holes, bolt holes through the inner end and also through the top wall of the metal body adapted to be brought into alinement with the holes in the outside end and reinforcements, a screw-threaded brace-rod passing through said alined holes, and means on said rod to hold diametrically opposite walls of said metal body in fixed relation to each other.

8. In a form for making concrete conductors, a one-piece sheet metal body portion having disconnected ends, said ends being lapped, outside reinforcements on the outer

lapped end, said outer end and reinforcements having threaded bolt holes, bolt holes through the inner end and also through the top wall of the metal body adapted to be brought into alinement with the holes in the outside end and reinforcements, a screw-threaded brace-rod passing through said alined holes, means on said rod to hold diametrically opposite walls of said metal body in predetermined fixed relation to each other, and means to vary the cylindrical diameter of the metal body.

In witness whereof, I have hereunto set my hand and seal at Indianapolis, Indiana, this 7th day of March, A. D. one thousand nine hundred and fourteen,

ALPHA LANGSTON. [L. S.]
